UNITED STATES PATENT OFFICE

LYDIA B. KOCH AND JOSEPH BUCHINA, OF NEW YORK, N. Y., ASSIGNEES TO THE REINFORCED PAPER BOTTLE CORPORATION, OF NEW YORK, N. Y., A CORPORATION

MANUFACTURE OF PAPER CONTAINERS

Application filed November 16, 1929. Serial No. 407,718.

Our invention relates to improvements in the manufacture of paper containers and particularly to the method of securing the flanged top in position.

5 The method consists shortly in inserting the flanged top, the flange of which is previously coated with adhesive rendered in a moist state into the top of the container so that the adhesive surrounding the flange of the top will be drawn backwardly around the flange and leave no portion of the adhesive to contact with the side of the container and consequently with the contents.

10 Heretofore it has been the custom in securing the flanged top in a container to coat the adhesive within the top edge of the container down a certain distance into it. This adhesive necessarily must be in a moist state when the flanged top is inserted in 15 the top of the container, and consequently the flange of the top as it is being forced into the container will force the surplus adhesive, where the flange fits the container closely as it should do in order to make a 20 proper seal, down below the top. A ring of adhesive, more or less irregular or broken, is thus projected into the container and necessarily gets mixed with the contents thereof, especially if such contents are in 25 the powdered or liquid form. This is objectionable for sanitary as well as other reasons. The adhesive is also drawn down from the top of the container, leaving it dry and impossible to twine inwardly to form 30 a beaded sealed edge, on account of the surface friction, see dotted lines in Figure 3.

35 Our invention is especially designed to overcome this defect.

40 Fig. 1 is a plan view of the top of the container previous to being formed up.

Fig. 2 is a perspective view of the upper portion of the container, and the top, as formed up, above it.

45 Fig. 3 is a vertical section of the container with the top inserted therein, the scale being very greatly exaggerated.

In the drawings like characters of reference indicate corresponding part.

50 The method which we employ is as follows:—

We first coat the top 1 with a margin of adhesive 2 of approximately the width of the flange to be formed and allow this margin to dry. We would, of course, treat as many tops as are necessary at one and the 55 same time. After such treatment the top is formed up with the flange 3 as indicated in Fig. 2 with adhesive on the outside periphery.

59 Before placing the top in position in the top of the container 4 we moisten the adhesive band 2 on the flange 3. We then insert the top and as the top is being inserted the adhesive band 2 on the flange 3 by contacting with the inner periphery of the container, which it is designed to fit closely, forces the adhesive and the surplus, if any, backwardly towards the top edge of the container and flange of the top. This results in not only forming a perfect seal between 65 the top edge of the flange and the top edge of the container but also insures that no adhesive will pass down into the container below the bottom of the top and be liable to mix with the contents. 75

The advantage of our method will now be apparent as it not only saves time in the manufacture and closure of the container but also insures the container from the admission of foreign matter into its contents 80 which is an important desideratum.

85 On reference to Figure 3, which represents, greatly exaggerated, the top of the container inserted in position, the manner in which the adhesive 2 is drawn back as shown between the flange and top, clearly illustrates the advantage of our invention, as no adhesive is caused pass inwardly below the bottom of the top of the container.

90 What we claim as our invention is:

The method of closing and sealing containers in which the top is formed with a vertical circumferential flange, consisting in coating the top with an adhesive of the 95 width of the flange previous to its being formed up, then allowing the adhesive to dry, then forming up the top so that the outer periphery of the flange fits tightly within the top edge of the container, then 100

moistening the flange and then inserting the flanged top into the top of the container so as to cause the adhesive thereon to recede from the bottom edge of the flange of the top towards the top edge of the flange of the top and top edge of the container.
